HAIR RECEIVER

Cloyd E. Burns, Stamford, Conn., assignor to
Schick Dry Shaver, Inc., Stamford, Conn., a
corporation of Delaware

Application August 7, 1937, Serial No. 157,857

5 Claims. (Cl. 30—41)

This invention relates to an improved attachment for a dry shaver of the type that includes an open inner cutter with a longitudinal bore into which cut hair passes during shaving.

5 The invention is designed to provide a receiver for such cut hair, the receiver being readily attached and readily detached, in order to allow the hair to be removed therefrom apart from the shaver. This latter feature is important 10 since many shavers are damaged at the thin blade portion of the shaving head by reason of the user tapping the shaving head on a table or basin, to dislodge the cut hair.

The invention is illustrated in the accompanying drawing of which Fig. 1 is an end view of a shaving head and adjacent portion of a shaver casing or handle with the hair-receiver applied to the head. Fig. 2 is a side view partly in section, of the parts shown in Figure 1. Figure 3 20 is a perspective view of one end of the receiver shown in Figures 1 and 2.

The shaving head used to illustrate the invention comprises an outer cutter 10 provided with teeth or blades 11, the cutter being shown as set 25 in a channel which extends across one end of the handle or casing of the shaver and secured by a set screw in the usual manner, as mentioned below. The outer cutter is hollow and receives the movable inner cutter 12 which is provided with teeth 13, which co-operate with the blades 11 when the inner cutter is moved longitudinally, to sever hair. The inside cutter is hollow and at least one end is open. The hair that is cut is deposited into the bore or 30 passage 14 of the inner cutter and in the absence of a hair receiver the cutter has been cleaned by blowing through the inner cutter or using a pipe cleaner or brush. If the latter is not available the user is prone to tap the shaving head on a hard surface to knock out the tiny cut stubble which congregates in the passageway 14. This tapping often results in damage to the cutters as the blades are extremely thin and are bent by such tapping.

40 Another feature of the shaver objected to by some users is that the stubble or short cut hair falls off out of the passageway 14 under different angles of use in shaving and falls on the clothing or on other surfaces and this in turn requires that the surfaces be cleaned.

In order to prevent this annoyance, to make it unnecessary to tap the shaver to clean it and to remove the cut hair, I install a readily removable hair receiver which does not interfere 45 with the operation of the shaver. The hair re-

ceiver can be removed from the shaver and cleaned and then easily replaced into its position on the shaver.

The hair receiver comprises a pair of pockets or wells which are preferably made of sheet 5 metal and are shown at 19. These pouches are shaped to fit in outline against the ends of the shaving head. The form illustrated shows a well known commercial type of shaving head with a tapered shape in cross section and the 10 pockets 19 are shaped to fit the ends of the outer cutter 10 as will be evident from Figure 1. The side of the pockets toward the cutter are open to allow free passage of hair into the wells. It will be evident that any other form of shearing head can be supplied with pockets that conform in outline to the ends of the fixed cutter. 15

The pockets are removable and can thus be readily installed or removed as necessitated by reason of repair or removal of the shearing head 20 from the shaver.

The form shown comprises a pair of pockets connected by side walls or strips 20 and 21 which are preferably integral with the pockets and adapted to lie alongside the outer surface of 25 the shearing head, that is, the side walls of the outer cutter and shaped to fit the outer faces of the shearing head.

Various means may be employed for securing the pocket in place and I illustrate an extension 30 22 which is perforated to receive a set-screw 23 now in common use in dry shavers for ready removal of the shaving head from the handle or casing and which is utilized for securing the hair receiver in place. The strips 21 assist in holding 35 the shearing head in place and all the parts are held securely against rattling or movement under vibration incidental to the operation of the electric motor inside the casing or handle of electric dry shavers. 40

Various changes can be made in the shape and proportion of the parts without departing from the scope of my invention.

I claim:

1. A hair receiver for open ended cutters of dry 45 shavers comprising hair receiving pockets adapted to fit on the ends of the cutter, a connection between said pockets extending longitudinally relative to the cutter for holding the pockets in place against the ends of the cutter and securing 50 means for said connection whereby the device can be readily removed from the cutter.

2. An open-center hair receptacle for attachment to the cutter-head of a razor, comprising spaced side-walls of resilient material and dis- 55

posed in converging planes, said side-walls terminating in end walls forming closed storage chambers, and said side-walls being adapted for frictional engagement with said head.

5. 3. A hair receiver for open-ended dry shaver shearing heads comprising pockets to fit against the ends of the shearing head, strips connecting the pockets for holding the pockets in place against the ends of the head, and a perforated 10 extension on one of said strips for securing the device on a dry shaver.

4. A hair receiver for open-ended dry shaver shearing heads comprising pockets fitting against the open ends of the shearing head, a connecting

15 strip connecting said pockets and fitting the outside of the shearing head and acting to hold the

pockets against the ends of the shearing head, and means for removably securing the connecting strip in place.

5. A hair receiver for dry shavers of the kind comprising a handle, a channel extending across one end of the handle, an open-ended cutter set in said channel and a thumb screw extending through a wall of the channel to hold said cutter in place, said receiver comprising a pair of open-sided pockets with their open sides fitting 10 against the open ends of the cutter, connecting means joining said pockets including a tab for engagement by said thumb screw to hold the receiver in position on the shaver.
